United States Patent Office

Des. 227,517
Patented June 26, 1973

227,517

AMMUNITION BOX

William J. Minneman, Montgomery County, Ohio
(Crestway Drive, Clayton, Ohio 45315)

Filed Apr. 5, 1971, Ser. No. 131,590

Term of patent 14 years

Int. Cl. D3—02

U.S. Cl. D87—1 R

FIG-2

FIG-6

FIG-7

FIG. 1 is a front perspective view of an ammunition box embodying my new design;

FIG. 2 is a rear elevational view;

FIG. 3 is a bottom plan view;

FIG. 4 is an enlarged fragmentary sectional view taken on the line 4—4 of FIG. 1;

FIG. 5 is an enlarged fragmentary sectional view taken on the line 5—5 of FIG. 1;

FIG. 6 is a top perspective view with the lid in open position; and

FIG. 7 is a view similar to FIG. 6 but showing another form of my new design wherein the interior only has been modified.

I claim:

The ornamental design for an ammunition box, as shown.
